UNITED STATES PATENT OFFICE.

ALFRED J. NEWTON, OF PROVIDENCE, RHODE ISLAND.

DESIGN FOR A COLLAR-HOLDER.

58,100.

Specification for Design.

Patented June 7, 1921.

Application filed January 3, 1921. Serial No. 434,807. Term of patent 14 years.

To all whom it may concern:

Be it known that I, ALFRED J. NEWTON, a citizen of the United States, residing at Providence, in the county of Providence and State of Rhode Island, have invented a certain new, original, and ornamental Design for a Collar-Holder, of which the following is a specification.

In the accompanying drawings which form a part of this specification—

Figures 1, 2 and 3 are a front elevation, a top plan view, and a rear elevation respectively of a collar holder embodying my new design.

I claim:—

The ornamental design for a collar holder, as shown.

ALFRED J. NEWTON.
